UNITED STATES PATENT OFFICE.

JOSEPH M. LITCHFIELD, OF SAN FRANCISCO, CALIFORNIA.

DESIGN FOR A BUTTON.

SPECIFICATION forming part of Design No. 25,115, dated February 4, 1896.

Application filed September 26, 1895. Serial No. 563,810. Term of patent 7 years.

To all whom it may concern:

Be it known that I, JOSEPH M. LITCHFIELD, a citizen of the United States, residing at San Francisco, in the county of San Francisco and State of California, have invented a certain new and useful Design for Buttons; and I do hereby declare the following to be a full, clear, and exact description of said invention, such as will enable others skilled in the art to which it most nearly appertains to make, use, and practice the same.

The drawing is the view of the front of a button having my design stamped thereon.

The leading feature of my design is the monogram of the interwoven letters "M" and

"S", as shown, the letter "S" being alternately passed over and under the legs of the letter "M," and the terminals of the letters being ball-shaped. This monogram is contained within a plain edge or rim.

20

Having thus described the invention, what I claim is—

The design for a button, substantially as shown and described.

In testimony whereof I hereunto set my hand this 30th day of August, 1895.

JOSEPH M. LITCHFIELD.

Witnesses:

C. H. PHILLIPS,
E. F. MURDOCK.
